UNITED STATES PATENT OFFICE

2,536,420

ADVERTISING DISPLAY AND METHOD FOR
MAKING SAME

Richard Burdick, Dallas, Tex.

Application August 27, 1947, Serial No. 770,909

11 Claims. (Cl. 154—95)

1

This invention relates in general to certain new and useful improvements in advertising display and to methods for making same.

It has recently become a widespread practice to employ the screen doors and window screens of commercial establishments as an advertising medium by inscribing thereon some type of advertising message or display. Frequently, manufacturers and wholesalers will supply push bars, hand plates, rails, kick plates and various other similar articles designed to be mounted upon the screen doors and bearing some display or advertising message relating to the products of such manufacturer or wholesaler. Wholesale bakeries, breweries and soft drink concerns frequently install in the screen doors of their retail distributors a section of wire mesh fabric in which an advertising display has been impressed or embossed by the use of paint pigments and similar plastic material. The installation of such a section of wire mesh fabric necessitates discarding the section of wire mesh fabric previously utilized in the screen door, with attendant waste and expense. Advertisers have frequently found the retailers are unwilling to discard existing screen doors or undergo the inconvenience of replacing existing screen door cloth with the screen cloth bearing the advertising display. Finally, the use of already imprinted screen cloth increases the shipping and distribution costs from the place of manufacture to the place of ultimate use and entails considerable inconvenience and expense attendant upon the installation of the imprinted screen cloth at the point of use.

The primary object of the present invention is to provide a simple and economical type of advertising display which may be permanently applied to foraminous surfaces, such as screen wire and the like.

It is also an object of the present invention to provide a simple and economical method for the manufacture, preservation, packaging and shipping of displays of the type above stated.

It is a further object of the present invention to provide an improved method whereby advertising displays can be applied upon a background of plastic material, either prior to or after the application of such plastic background, to a wire mesh fabric.

It is an additional object of the present invention to provide a plastic background material which may be readily packaged and shipped and may be quickly and conveniently applied to wire mesh fabric to form a plaque like element for receiving a decalcomania or other advertising display.

2

Other objects and advantages of the present invention will be pointed out in the detailed description thereof, as set forth in the following specification and the claims hereunto appended.

Figure 1 is a perspective view of a sheet of paper having a decalcomania, literal symbol or similar advertising display placed thereon.

Fig. 2 is a similar view showing the plastic background material in place over the decalcomania, literal symbol or similar advertising display.

Fig. 3 is a perspective view of the finished display unit ready for shipment to point of ultimate use.

Fig. 4 is a transverse view of the display unit taken on line 4—4 of Fig. 3.

Fig. 5 is a fragmentary transverse sectional view of the display unit installed upon a section of wire mesh fabric prior to removal of the outer covering sheet.

Fig. 6 is a fragmentary perspective view of a section of wire fabric having the display unit permanently installed thereon.

Fig. 7 is a transverse sectional view of a modified form of the display unit; and

Fig. 8 is a transverse sectional view of a piece of wire mesh fabric with two marginally registering display units superimposed thereon in back to back relation for providing a double reading advertising display or sign upon the wire mesh fabric, said units being shown prior to removal of the outer covering sheets.

In carrying out the present invention, a sheet of suitably coated impervious paper, such as wax paper, 1 is placed upon a table or other flat working surface and a decalcomania 2 may be placed thereon, or a literal symbol, design or advertising display may be superimposed thereon by screen stencilling or any other conventional method. It should be noted that the decalcomania, symbol, design or advertising message is placed upon a sheet face down, or in reverse so to speak, so that its upwardly placed or visible side is in reverse all for purposes presently more clearly apparent. Thereupon a thin layer of background material 3 is applied over the decalcomania, symbol, design or advertising message 2 in a defined area and in a relatively thin layer. For purposes of illustration, as shown in Fig. 2, the background 3 is depicted in the form of a slice of bread as might be utilized in the advertisement of a wholesale baker. It will of course be understood that the shape of the background may assume any desired contour and may be applied by screen stencilling or any other conventional method. The plastic compound may

be an extremely heavy paste-like mixture of paint pigments, varnishes and drying oils commonly used in the screen process art, or may consist of a heavy paste-like compound of pigments suspended in a nitrocellulose base similar in character to a heavy lacquer, although in the latter case slow drying solvents must be included so that the background will remain plastic, or at least semi-plastic, for a substantial period of time.

Finally, a second sheet of impervious suitably coated paper 4 is placed over the section of background material to form an entire display unit in which the plastic background is enclosed between the two paper sheets 1 and 4. The unit may be shipped in a small compact package to the point of actual use, whereupon the rear covering sheet 4 may be peeled off and the exposed face of the still plastic background material pressed into proper location in the wire mesh fabric 5 of a screen door. As pressure is applied to the outwardly presented face of the outer or front covering sheet 1 the plastic background material will flow sufficiently to be forced into the interstices of the wire mesh fabric 5, substantially as shown in Fig 5. Thereupon the section of background material 3 is allowed to dry and then the outer or front covering sheet 1 is removed exposing to view a completed advertising display unit, as shown in Fig. 6. It should be pointed out in this connection that the paper sheets 1 and 4 should be coated with wax or other material which is relatively non-adherent to the decalcomania, literal symbol, design or advertising display 2 and is relatively non-adherent to the background material 3, so as to permit such paper sheets 1 and 4 to be peeled off, incident to installation of the advertising unit upon the user's screen door. It has been found that the section of plastic background material 3 will not dry out or harden readily so long as both of its large-area faces are securely covered by the paper sheets 1 and 4. There will, of course, be some tendency for the section of background material 3 to dry out around the lateral edges between the paper sheets 1 and 4, but this latter drying will not be sufficient to destroy the plasticity of the material within a reasonable period of time. Samples of advertising units prepared in the above manner have been stored for as long a period as eight to ten months without any appreciable change in the plasticity of the background material. It will be understood that the paper sheets 1 and 4 may, if desired, be covered with a non-adherent powder which may readily be washed off after the advertising unit has been installed in the screen wire.

If it should be desired to provide an advertising unit which may be stored for extraordinary long periods of time or may be subjected to weather conditions conducive to rapid drying out of the plastic material, a unit having paper sheets 1', 4', may be provided in which the peripheral edges are sealed together as at s, thereby completely enclosing the unit and effectively preventing hardening of the plastic background material 3', all as best seen in Fig. 7.

It will also be understood that two advertising units may be installed in peripherally registered back to back relation upon a single section of screen wire 5' and when dry the paper sheets 4, 4, may be removed to provide a so-called "double reader," that is to say, an advertising display having oppositely placed faces

each bearing an advertising message and being respectively visible or readable from opposite sides of the screen door.

It will also be apparent that, according to the present invention, I may stencil or otherwise superimpose the section of plastic background material 3 directly upon the paper sheet 1 omitting the decalcomania, literal symbol, design or advertising display 2 and superimpose the covering sheet 4 directly over the section of plastic

background material 3 to form an unlettered or blank background unit which may be installed in the screen door in the same manner as that previously described and when dry is adapted to receive either a decalcomania, literal symbol or even a hand lettered advertising sign as may be desired.

Having thus fully described the present invention, what I claim and desire to secure by Letters Patent is:

1. A self-contained advertising display unit adapted for ultimate installation upon a foraminous supporting member, which unit comprises a decalcomania and a substantially flat section of slow-drying plastic material superimposed upon the rear side of said decalcomania to form a background therefor, a removable covering sheet disposed upon the forward face of the decalcomania and extending over and beyond the peripheral limits of the background, a similar removable covering sheet disposed upon the rear face of the background and beyond the peripheral limits thereof said covering sheets being marginally secured to each other whereby to enclose said flat section during storage and handling prior to installation.

2. A self-contained advertising display unit adapted for ultimate installation upon a foraminous supporting member, which unit comprises a decalcomania and a substantially flat section of plastic material superimposed upon the rear side of said decalcomania to form a background therefor, a covering sheet disposed upon the forward face of the decalcomania and extending over and beyond the peripheral limits of the background, a similar covering sheet disposed upon the rear face of the background and beyond the peripheral limits thereof said covering sheets being marginally secured to each other whereby to enclose said flat section during storage and handling prior to installation.

3. A self-contained advertising display unit adapted for ultimate installation upon a foraminous supporting member, which unit comprises literal characters and a substantially flat section of plastic material superimposed upon the rear side of said literal characters to form a background therefor, a removable covering sheet disposed upon the forward face of the literal characters and extending over and beyond the peripheral limits of the background, a similar removable covering sheet disposed upon the rear face of the background and beyond the peripheral limits thereof said covering sheets being marginally secured to each other whereby to enclose said flat section during storage and handling prior to installation.

4. A self-contained advertising display unit adapted for ultimate installation upon a foraminous supporting member, which unit comprises an advertising display and a substantially flat section of plastic material superimposed upon the rear side of said advertising display to form a background therefor, a removable covering sheet disposed upon the forward face of the

advertising display and extending over and beyond the peripheral limits of the background, a similar removable covering sheet disposed upon the rear face of the background and beyond the peripheral limits thereof said covering sheets being marginally secured to each other whereby to enclose said flat section during storage and handling prior to installation.

5. A self-contained advertising display unit adapted for ultimate installation upon a foraminous supporting member, which unit comprises a decalcomania and a substantially flat section of plastic material superimposed upon the rear side of said decalcomania to form a background therefor, a removable covering sheet disposed upon the forward face of the decalcomania and extending over and beyond the peripheral limits of the background, a similar removable covering sheet disposed upon the rear face of the background and beyond the peripheral limits thereof, the extended peripheral margins of said sheets being sealed to each other for enclosing said advertising display unit.

6. The method of forming an advertising sign upon a section of foraminous material which comprises laying a decalcomania upon a sheet of paper coated with a material capable of rendering it substantially nonadherent to said decalcomania, superimposing thereon a thin layer of plastic background material having a defined area, thereupon superimposing upon the exposed surface of the plastic background material a second sheet of paper, securing the marginal edges of said sheets to each other whereby to enclose said plastic material to prevent drying out thereof, subsequently removing said second named sheet of paper at the point of use, pressing the exposed still plastic face of the plastic background material into a foraminous sheet, allowing the plastic background material to dry, and thereupon removing the first named sheet thereby revealing the advertising message.

7. The method of forming a "double-reading" advertising sign upon a section of foraminous material which comprises forming a pair of background plaques while in a relatively soft state in which they are capable of being deformed under manually applied pressure said plaques further of substantially the same peripheral contour and having outwardly presented relatively flat surfaces for receiving an advertising message, placing said plaques in back-to-back marginally registered relation upon opposite sides of a piece of foraminous material with the smooth sides presented outwardly in opposite directions to each other and pressing said plaques together while still plastic so as to force the inward plastic portions of the plaques into the interstices of the foraminous material, and merging one with the other.

8. The method of forming a "double-reading" advertising sign upon a section of foraminous material which comprises forming a pair of background plaques while in a relatively soft state in which they are capable of being deformed under manually applied pressure said plaques further of substantially the same peripheral contour and having outwardly presented relatively flat surfaces for receiving an advertising message, placing said plaques in back-to-back marginally registered relation upon opposite sides of a piece of foraminous material with the smooth sides presented outwardly in opposite directions to each other and pressing said plaques together while still plastic so as to force the

inward plastic portions of the plaques into the interstices of the foraminous material, merging one with the other, and allowing said plaques to dry and become rigid.

5. The method of forming a "double-reading" advertising sign upon a section of foraminous material which comprises forming a pair of background plaques of plastic material capable of being deformed under manually applied pressure and thereafter drying and becoming relatively rigid upon exposure to atmosphere, said plaques being of substantially the same peripheral size and shape and having outwardly presented relatively flat surfaces for receiving an advertising message, placing said plaques in back-to-back marginally registered relation upon opposite sides of a piece of foraminous material with the smooth sides presented outwardly in opposite directions to each other and pressing said plaques together while still plastic so as to force the inward plastic portions of the plaques into the interstices of the foraminous material, and merging one with the other.

10. The method of forming a "double-reading" advertising sign upon a section of foraminous material which comprises forming a pair of background plaques of plastic material capable of being deformed under manually applied pressure and thereafter drying and becoming relatively rigid upon exposure to atmosphere, said plaques being of substantially the same peripheral size and shape and having outwardly presented relatively flat surfaces, imprinting upon said flat surfaces an advertising message, placing said plaques in back-to-back marginally registered relation upon opposite sides of a piece of foraminous material with the smooth sides presented outwardly in opposite directions to each other and pressing said plaques together while still plastic so as to force the inward plastic portions of the plaques into the interstices of the foraminous material, and merging one with the other.

15. The method of forming a background plaque capable of installation in situ upon a section of foraminous material, which method comprises forming a thin layer of plastic material of defined area upon, and wholly within the peripheral limits of a sheet of material the surface of which has been coated to render it non-adherent to said plastic material, superimposing upon the uncovered face of said layer a second sheet of material the surface of which has been coated to render it non-adherent to said plastic material, said second sheet being substantially identical in size to the first sheet, and sealing the peripheral edges of said sheets to each other for entirely enclosing the plastic background plaque.
